UNITED STATES PATENT OFFICE

GEORGE H. WILLETS, OF BEAVER FALLS, PENNSYLVANIA

TOURIST TABLE AND SUPPORT THEREFOR

Application filed August 18, 1930. Serial No. 476,047.

This invention relates to tourists' tables and more particularly to improved supports for such tables intended for travellers in railway coaches.

5 The invention has for its objects, among others; first, to provide a table for facile packing and portability; second, to provide such a table adapted for facile and secure support on the wall of a railway car; third, 10 to provide a support for such a table specially adapted to secure said table against the wall of a railway car by means of the curtain-guide-grooves; fourth, to provide such a table and support capable of being folded 15 into a compact portable form; fifth, to provide adjustability for various designs of railway-car-windows; sixth, to provide a simple manual adjustability; seventh, to provide such a device of suitable strength and 20 durability, but light in weight; and eighth, to provide such a device that possesses low manufacturing cost. Other objects may appear as the description proceeds and the various elements of construction are set forth.

25 I provide a tourist table having a horizontal table surface of appreciable area one end of which is adapted to rest against a vertical surface; a part is hinged to the table and provided with two supporting flanges 30 having tabs that extend beneath the table to support it; hook rods rotate in holes in the flanges at the rear of the vertical portion and are adjustable lengthwise with reference to each other, thus providing a wide 35 range of adjustability for the hook rods which are adapted to cooperate with any suitable support such as grooves, holes, contrary-angled surfaces and the like, but more especially with the curtain-guide-grooves 40 placed at either side of a railway-car-window. My tourist table and support therefor are obviously particularly adapted for the space between railway car chairs.

45 Reference is now made to the drawing, which is hereby made a part of this specification, in which is shown one embodiment of my invention, like numerals of reference referring to like parts throughout the drawing, in which

50 Figure 1 is a left perspective view showing

my tourist table supported by means of one of the curtain-guide-grooves of a Pullman railway car, the other groove being not shown,

Figure 2 is a left end elevation showing 55 the support and its attachment,

Figure 3 is a section on the line 2—2 of Figure 1 viewed from the left,

Figure 4 is a plan view showing the tourist 60 table folded for packing, and

Figure 5 is an enlarged view similar to that of Figure 3 showing the construction of the clamp for locking the supported arms in any adjusted position.

The table 1 is of wood or any suitable material and is preferably one board of any desired size and dimensions and suitable finish. Hinged thereto at a point somewhat removed from the left end is a smaller board 3 of the same width as table 1 but of a length of only 65 six or eight inches. Two hinges 5 secure the board 3 to the table 1 rotatably through an angle of ninety degrees. On either end of board 3 is a metal flange 4 similar to the other except that the tab 6 is turned under in one direction and on the other is turned in the opposite direction, the two tabs 6 thereby forming stops preventing the board 3 being turned from the table 1 more than a right angle or vice versa. Screws 20 secure the 70 flanges 4 to the ends of board 3 and screws 22 secure the hinges 5 to the table 1 and the board 3. It is now apparent that I provide a table having a hinged part attached thereto which may be folded flat against the table 75 or moved into the vertical position and that when in the vertical position the table itself is suspended therefrom and supported against movement below a flat plane.

The flanges 4 have extensions projecting to 80 the rear of the vertical board 3, each provided with two holes 24 one near the other which are adapted to provide bearings for the rods 7 and 8, which have right angled extensions 7a and 8a which in turn terminate in hooked 85 ends 7b and 8b as clearly shown in Figures 2 and 4. A clamp 12 is provided with two transverse grooves 25 spaced about the same distance apart as are the holes 24 in one of the flanges 4 and rod 8 lies in the upper hole 90 100

24 of one flange 4 and the upper groove of
clamp 12 and the rod 7 lies in the lower hole
24 of the opposite flange 4 and in the lower
groove 25 of clamp 12. A bolt 23 passes
8 through the center of clamp 12 and the board
3 and a flange 9, which is secured to board 3
by screws 21, and terminates in screw threads
10 on which is serrated thumb nut 11. It is
apparent now that by turning the thumb nut
11 tight against the flange 9 the clamp 12
presses both rods 7 and 8 tight against the
back of board 3 and therefore secures them
against rotation or lengthwise motion. This
clamping action is shown in Figure 5.

15 In Figure 1 there is shown the railway car
wall 14 and at the side of the window a cur-
tain-guide-groove 15. Window casing 16 and
glass 17 are shown in part also. To attach
the table 1 on the wall at about the height
20 of the window sill 18, board 3 is turned to
a vertical position, rods 7a and 8a are also
turned upward after loosening the thumb
nut 11; then the hook end 7b is placed in
groove 15, and the part 8a is pulled away so
25 that the hook end 8b may be placed in the
groove of the adjacent window (not shown)
after which rod 8 is pushed back into normal
position by grasping extension 8a, after
which the height of the table 1 is adjusted
30 by the tourist as desired and thumb nut 11 is
turned home to fix the arms 7 and 8 in position.
At 13 is shown a cutaway end in table
1 so that the end may be fixed more securely
35 in case of an irregular wall 14 against oscil-
lation in a horizontal plane.

To fold the table the thumb nut 11 is loos-
ened and one of the rods moved out to release
its hook end from the groove and the board
3 is folded down and the rods 7 and 8 folded
40 back to the position shown in Figure 4 in
which it is seen that I provide a compact
unit easily carried and packed for travel.

Although I have shown only one form of
my improved tourist table I have contem-
45 plated and constructed many different de-
signs, and have provided additional exten-
sions and supporting hooks and other appur-
tenances of convenience to the tourist, and
changes will readily occur to those skilled in
50 the art within the scope of my invention,
so therefore I do not choose to limit myself
except as in the appended claims.

I claim:

1. In combination, a table comprising a
55 part adapted to lie against a vertical wall
between adjacent windows, and a support
attached to said part, said support comprising
two arms each of which has an angled ex-
tension, one to the right and one to the
60 left and adapted to enter the curtain-guide-
grooves of adjacent railway-car-windows.
2. In combination, a table comprising a
part adapted to lie against the wall between
adjacent windows, and a support attached
65 to said part, said support comprising two

arms each of which has an angled extension,
one to the right and one to the left and adapt-
ed to enter the curtain-guide-grooves of ad-
jacent railway-car-windows, the distance be-
tween said arms being adjustable to different
70 widths of wall.

3. In combination, a table comprising a
part adapted to lie against the wall between
adjacent windows, and a support attached
to said part, said support comprising two
75 arms each of which has an angled extension,
one to the right and one to the left, and
adapted to enter the curtain-guide-grooves
of adjacent windows, the distance of said
angled extensions from the wall being ad-
justable and the distance between said arms
80 being adjustable, substantially as described.

4. In combination, a table comprising a
vertical extension, two rods pivotally at-
tached thereto, each of said rods carrying
a right-angled extension adapted to fit in
the curtain-guide-groove of a railway-car-
window, the extension on the left rod being
85 angled to the right and the extension on the
right rod being angled to the left, and means
for securing said rods in the pivotally ad-
justed position.

5. In combination, a table comprising a
vertical extension, two rods pivotally at-
tached thereto, each of said rods carrying a
right-angled extension adapted to fit in the
90 curtain-guide-groove of a railway-car-win-
dow, the extension on the left rod being angled
to the right and the extension on the right
rod being angled to the left, means for
securing said rods in the pivotally adjusted
95 position, means for adjusting the distance
between said angled extensions, and means
for securing said rods in the spaced apart
100 position.

6. In combination, a table comprising a
vertical extension, two rods pivotally at-
tached thereto, each of said rods carrying
an angled extension adapted to fit in the cur-
tain-guide-groove of a railway-car-window,
105 the extension on the left rod being angled to
the right and the extension on the right rod
being angled to the left, the distance be-
tween said angled extensions being adjust-
able, and means for securing the angled ex-
110 tensions in an adjusted position.

7. A portable table comprising two parts
hinged together, a stop adapted to prevent
said parts from being opened beyond a pre-
determined angle, rods pivotally connected
with one of said parts, said rods having an-
gled extensions adapted to mount said table
115 on the wall by means of the curtain-guide
grooves of adjacent windows.

Signed at Beaver Falls in the county of
Beaver and State of Pennsylvania this fif-
teenth day of August, A. D. 1930.

GEORGE H. WILLETTs.
